ADJUSTABLE DOOR STAY

Benno M. Vollmer, Waukegan, Ill.

Application January 20, 1948, Serial No. 3,241

3 Claims. (Cl. 292—262)

1

This invention relates to a door stop or door check, adaptable for use to limit the axial movement of any type of hinge door, such as a house door, a cabinet door, lids, trunks or the like.

The principal object of this invention is to retain a hinged door in any desired open position and to prevent the door from swinging on its hinge back into a closed position.

Another object of this invention is to limit the arcuate axial movement of the door on the hinges so as to define the angle or opening.

Another object of this invention is to provide an adjustable door stop, whereby an easy adjustment may be facilitated to change or regulate the desired angular opening of the door.

Another object of this invention is to provide a door stop or door check, which is concealed, except when the door is opened, and even then is semi-concealed, in that it is connected between the abutting faces of the door and door casing.

A meritorious feature of this invention resides in the provision of a door stop or door stay, having its operative assembly housed within a recess formed in the door casing, and which is adjustable for defining the axial movement of the door, hingedly attached or secured to the door casing, and which is adjustable for locking or maintaining the door in any desired position, with its face removed or spaced from the complementary face of the casing.

These and ancillary objects and other meritorious features are attained by this invention, a preferred embodiment of which is described in the following description, by way of example only, and illustrated in the accompanying drawings, wherein:

Figure 1 is a top plan view of a fragmentary portion of a door hingedly secured to a door casing, with a door check, constructed according to the principles of this invention, shown in operative position therein, in dotted lines;

Figure 2 is a top plan view of a door hingedly secured to the casing, showing the invention in an operative position;

Figure 3 is a transverse sectional view of the door casing, showing in greater detail the structure of this invention; and,

Figure 4 is a perspective view of the connecting link or member, connecting the door check structure and the casing check structure.

It is well-known that many doors, which are hingedly attached to a door casing or other suitable support, at times, after being opened, return to their closed position with undue haste and cause undue consternation and bodily harm.

2

To obviate this defect and also to maintain the door in a locked open position, there has been devised a number of door checks or stops. For many reasons, such as the unsightliness of the door check assembly connected between the door casing and the outer side of the door, the inability of door checks to maintain the door in an open position, due to the heavy weight of the door, the short life of the door checks caused by the constant and repetitious opening of the door, which tends to bind or grate the connecting structure, the door checks or door stops devised did not prove fruitful.

Therefore, it is the primary purpose of this invention to provide an improved door check or door stop, which has its locking assembly housed within a recess formed in the door casing so as to be concealed except when the door is opened and even then, to be semi-concealed between the angular opening formed by the casing base and the door face, which abut together, when the door is closed. Also, it is the purpose of this invention to provide a durable and efficient door check that will conveniently and efficiently prevent the arcuate or axial movement of the door on the hinges away from the door casing, so that the axial movement of the door is controlled and limited, thereby obviating the tendency of the door to swing completely around on the hinges and bind or break the hinges or cause other material damage.

Referring now more particularly to the drawings, wherein a preferred embodiment of this invention is shown for illustrative purposes, and wherein similar characters designate corresponding parts throughout, there is shown a door casing, 16, to which is hingedly secured by hinges 14, a door 12, all of the aforementioned components being of conventional and customary structure. A door stop or check constructed according to the principles of this invention and generally denoted by the character reference 10 is shown in attachment between the abutting faces 13 and 20 of the door and door casing respectively.

This door check or stop comprises an elongated longitudinally extending threaded tube or rod 22, which is slidably housed within a rectangular recess, of suitable dimensions, and having opposing side walls 26 and 28, disposed and arranged within the casing. A sleeve 24 of suitable material, is arranged around the side walls of the recess and may comprise any type of friction material, 30, having its outer ends flanged and inserted within notches formed in the abutting face of the casing.

3
The tube or rod 22, which is suitably threaded, is slidably received within the recess and has a pair of opposing tapering nuts 32 and 34 which are threadably received on the tube, for longitudinal adjustment thereon. A longitudinally split or open resilient band, 36, is disposed about the elongated tube or rod 22, and has its opposing ends received around the tapering portions of the nuts 32 and 34. This sleeve or band 36 may comprise any suitable material, such as a resilient spring steel expansion band, which is provided for frictional or locking engagement with the frictional sleeve 30, secured to the opposing side walls 26 and 28 of the rectangular recess 24.

Disposed on one end of the threaded rod 22 is an arcuate head portion 38, having a centrally disposed aperture formed therein.

Suitable means are provided to retain the door in limited or controlled engagement with the casing and the assembly slidably received within the casing and includes an elongated faired screw 40 having a forwardly projecting arcuate head portion 42, which has a centrally disposed aperture formed therein.

Suitable means are provided to connect the apertured head 38 of the tube or rod 22 with the apertured head 42 of the faired screw 40 and include a connecting member, generally denoted by the reference character 44. The connecting member or assembly comprises a body section 46 of cylindrical shape, having an elongated axially formed threaded bore formed at one end thereof. Projecting outwardly or forwardly of the opposing end thereof formed integrally with the body section 46 is a clevis or eye member 48. Adjustably received in the threaded bore 50 formed in the opposing end of the body section 46, is a clevis or eye member 52, having a threaded shank 54 which is adjustably screwed or threaded into the bore 50. The clevis 52, and its threaded shank 54 are adjustably secured to the body section 46 thereby.

Thus it can be seen that when the door 12 is closed and the respective faces 18 and 20 of the door and the casing abut each other, the stop or check assembly is concealed and is rendered non-visible. When the door 12 is open and swings on the hinges 14 in an arcuate angular movement away from the casing 16, the tube or rod 22, having the tapering nuts 32 and 34 adjustably received thereon, will be moved a proportional distance from the housing or recess 24. With reference to Figure 2 of the drawings, it can be seen that when the door is at right angles to the casing, the assembly 10, unless the connecting member 44 is otherwise adjusted or extended, will limit the movement of the door away from the casing and at the same time, will prevent the door from returning or swinging back on the hinges 14 for a short duration. However, the assembly will not retain the door in the angular position shown in Figure 2, but will allow the door to swing back on the hinges to a closed position, unless the locking or retaining means are moved into an operative position. To do this would entail only the rotating of the tapered nut 34, so as to move the tapering end further within the inner surface of the resilient steel band 36 and thereby spread the band further apart, until the sides of the band were in frictional or locking engagement with the sleeve formed on the side walls 26 and 28 of the recess 24. Thus it can be seen that when this locking adjustment is made, the door 12 will be

4
prevented from moving from the open position to a closed position, unless of course, a heavy manual pressure is applied thereto. However, the assembly will prevent the swinging or moving of the door, usually caused by the wind or accidental jarring or the like.

To define a greater axial movement of the door on the casing, so that the door may be allowed to move on the hinges to form a greater angle than a right angle, but at the same time the surfaces of the respective door and casing will be prevented from touching, so as to bind or break the hinges 14, the pivot pin 56, which secures the pivotal connection between the apertured head 38 and the clevis 52 is removed. Then, the clevis 52 is rotated so that the threaded shank 54 is removed a spaced distance from the threaded bore 50, constructed and arranged in the body portion 46 of the connecting member 44.

It is thus apparent that there has been provided an efficient and durable means for checking or halting the axial or angular movement of a door on its hinges away from the casing and also an efficient and durable means for maintaining the door in any selected open position.

Of course, since many other modifications and purposes will become apparent to those skilled in the art upon a perusal of the description, in view of the accompanying drawings, it is to be understood that certain changes in style, shape and structure may be effected without a departure from the spirit of the invention and within the scope of the appended claims.

Having described the invention what is claimed as new is:

1. A door check for a door hinged on a door casing, said casing having a lined cylindrical recess formed therein, comprising a threaded rod slidably housed in the recess, a longitudinally split resilient band disposed concentrically around the rod and adapted to frictionally engage the sides of the lined recess, a pair of longitudinally adjustable members disposed on the rod and adapted to engage the opposing ends of the band and spread the band apart, an apertured head portion on one end of the rod, a connecting member having oppositely projecting paired eye members, one of the eye members being pivoted to the head of the rod, a fastening member adapted for insertion in the door, the other eye member being pivoted to said fastening member, means for adjusting the connecting member to control the arcuate travel of the door.

2. A door check for a door hinged on a door casing, said casing being formed with a lined cylindrical recess, comprising a threaded rod slidably housed in the recess, a longitudinally slotted resilient band disposed concentrically around the rod, a pair of inwardly tapered members received on the rod and longitudinally adjustable thereon for engagement under the ends of the band and selectively moving the resilient band in and out of frictional engagement with the lined side walls of the recess, a fastening member inserted in the door, an adjustable connecting member pivoted to the tube and fastening member.

3. A door check for a door hinged on a door casing, said casing having a lined cylindrical recess formed therein, comprising a threaded rod slidably housed in the recess, a longitudinally slotted resilient band disposed around the rod, a pair of inwardly tapered nuts received on the

rod and longitudinally adjustable thereon relative to each other for engagement under the opposing ends of the band for selectively moving the resilient band in and out of frictional engagement with the lined side walls of the recess, a fastening member inserted in the door, a connecting member pivoted to the rod and member, said connecting member including a body section having a projecting clevis formed integrally at one end, an axially threaded bore formed in the other end of the body section, a clevis having a threaded shank adjustably secured in said bore.
